UNITED STATES PATENT OFFICE.

SIMEON C. LAWLOR, OF CHICAGO, ILLINOIS, ASSIGNOR TO SARAH A. LAWLOR, OF CHICAGO, ILLINOIS.

MOP-WRINGER.

1,082,465.

Specification of Letters Patent.

Patented Dec. 23, 1913.

Application filed February 24, 1912. Serial No. 679,707.

To all whom it may concern:

Be it known that I, SIMEON C. LAWLOR, citizen of the United States, residing at Chicago, in the county of Cook and State 5 of Illinois, have invented certain new and useful Improvements in Mop-Wringers; and I do hereby declare the following to be a full, clear, and exact description of the invention, such as will enable others skilled 10 in the art to which it appertains to make and use the same.

This invention relates to improvements in wringers, and particularly to such as are adapted for use in coöperative relation to a 15 receptacle adapted to receive the exuded fluid, the invention being designed more particularly for the wringing of mops.

To this end, an object in view is the provision of means causing the parts of the 20 wringer to assume a position when not in use adapted to facilitate the introduction of a mop.

With this and further objects in view, the 25 invention comprises certain novel constructions, combinations and arrangements of parts as will be hereinafter described and claimed.

In the accompanying drawing,—Figure 1 is a view in side elevation of a wringer 30 embodying the features of the present invention. Fig. 2 is a top plan view thereof.

Referring to the drawing by numerals, 1 indicates a pail or receptacle supporting base which is formed of a strap 1^a set on 35 edge, preferably of metal, and cross straps 1^b, 1^b, connecting opposite points of strap 1^a and forming the bottom or supporting portion of the base upon which the pail or other receptacle 2 is designed to be sustained. The 40 base 1 is carried preferably on casters 3, 3, whose stems are journaled in supporting brackets 4, 4, each consisting preferably of a metallic strap formed with a loop or bend at its upper end inclosing the strap 45 1^a and extending downwardly and being formed into a loop presenting two spaced horizontal portions which are perforated for the reception of the stem of the respective caster 3. The upper loop of bracket 4 is 50 preferably riveted to the strap 1^a, and the brackets are spaced about the base 1 suitably for supporting the same.

Upstanding from each side of the base 1 is a side frame, which, for facility of manufacture, may consist of a standard 5, and a

standard 6, which are merely continuations of the straps 1^b, 1^b, the said straps being riveted to the strap 1^a at the lower end portions of the standards. For facilitating disposition of the operating parts at the upper 60 end of the side frames, each standard 5 is preferably perfectly upright, that is rises vertically from the base, while each standard 6 is formed laterally arcuate or curved 65 to cause its upper end to approach the upper end of the respective standard 5, and the two standards are connected by a plate 7 which is riveted to both standards. A cross bar or rod 8 connects the two plates 7, having its ends fixed to the respective plates as 70 by a shoulder at one side of the plate, and a swaged head at the other, not herein illustrated. Each plate 7 extends vertically 75 above the respective standards 5 and 6, and is bent to a horizontal position across the upper ends thereof, and then again bent to an upstanding position, the last named part of the respective plate 7 being slotted, as at 9, forming guiding cam plates 10 and 11. The horizontal portion of each plate 7 is 80 slotted, as at 12, for receiving and guiding an actuating arm hereinafter mentioned.

A bail-like lever 13 has its ends pivoted, as at 14, to the standards 6, and its intermediate portion outstanding above the base 85 1, and provided with a suitably attached tread plate 15. Pivoted to the respective sides of the bail 13, intermediate the pivot point and the tread plate, are the respective upstanding arms 16, 16, which extend 90 through and are guided by the respective slots 12, the slots being of a size loosely accommodating the arms, but of sufficiently snug fit to prevent any excessive lateral or edgewise play. Each arm 16 is bent edge- 95 wise substantially midway of its length, as at 17, for causing the upper end of each arm to travel laterally a greater distance than it would otherwise travel for the purposes hereinafter mentioned. It is to be noted also 100 that the connection at the lower end of each arm 16 is spaced from the respective pivot 14 a distance sufficient for causing the lower end of each arm to always remain outside the vertical, transverse planes of the slots 105 12, so that each arm 16 extends on an incline longitudinally through the respective slot. A spring 18 is preferably arranged at each side frame and has its upper end connected to the respective standard 6 adjacent plate 7, 110

and its lower end connected to lever 13 intermediate its respective pivot and the respective arm 16, the springs 18 being tensioned to maintain the lever 13 in its raised position.

A wringer roller 19 extends across from one side frame to the other and is journaled in the plates 11 at one side of slots 9. A similar roller 20 is journaled in the upper 10 ends of the arms 16, one of the journals of roller 20 extending beyond the respective arm and being formed into an operating crank 21. The journals of each roller 19, 20, preferably consist of a reduced shaft 22 15 fixed to and outstanding from a disk 23 which is in turn fixed to the respective roller, as by screws 24, 24. Each roller 19, 20, is thus sufficiently short to lie between the plates 11, 11, 10, 10, without end contact 20 therewith, the reduced journals 22 engaging the respective plates. The upper edges of the plates 10 are rounded off to form cams or guiding plates, and in operation are engaged by the respective journals 22 during 25 reciprocal movement of the arms 16.

A rod 25 is carried by each plate 7 and extends inwardly therefrom below the rollers 19, 20, and is bent backwardly, that is in a direction toward and beneath roller 19 30 for serving as mop guides, the said rods extending over the edges of the pail 2, so as to insure disposition of the mop within the pail without necessitating grasping the mop by the hand of the operator.

In operation, the parts being in the position seen in full lines in the drawing, the operator lifts the mop merely by the use of the handle or mop stick and lowers the mop cloth between the rollers 19, 20, down into 40 the pail 2. After the mop has been introduced for its full length, the operator places his foot on tread plate 15 and lowers the lever to the position indicated in dotted lines in Fig. 1, whereupon the parts assume the 45 dotted line position as indicated in both figures. During this lowering movement of lever 13 the arms 16 have been drawn downwardly, being guided first by contact of the front edges of the arms with the front ends 50 of the slots 12 until the journals 22 of roller 20 have come in contact with the upper edges of plates 10, whereupon the said plates serve as guides, so that the final relative 55 position of the rollers, as indicated in dotted lines, is assured. Thus the downward pressure on the lever 13 tends to draw the roller 20 toward roller 17, and if an interposed mop prevents the full movement of roller 20, the amount of pressure exerted by 60 the foot on the lever 13 will govern the degree to which the mop may be exhausted of its moisture by virtue of the capacity for varying degrees of pressure on the mop. As soon as the mop has been firmly clamped 65 between the rollers, the operator rotates the

rollers by actuation of crank 21 until the mop has been fed backwardly or upwardly out of the rollers. Thereupon the operator removes his foot from tread plate 15, and the lever 13 is drawn by springs 18 back to 70 its former position with the connected parts restored to the position indicated in full lines.

It is to be noted that the incline of the arms 16 causes the roller 20 to travel forwardly or away from the roller 19, in addition to its upward movement, and the bend 75 17 in the arms 16 effects an increase in the lateral spacing apart of the rollers. The advantage gained is thought to be obvious in 80 the providing of an open space between the rollers wherein a mop may be introduced vertically.

What I claim is:—

1. In a wringer, the combination with 85 wringer rollers, a fixed support for one of the rollers, rigid arms rotatably sustaining the other roller, each of said arms being bent intermediate its ends in a direction causing the roller engaging portion of the arms to 90 be disposed away from the fixedly supported roller, guides for the arms surrounding the same, and means for thrusting the arms longitudinally through the guides to an extent causing the bent portions to pass the guides, 95 whereby the roller carried by said arms is adapted to be moved laterally away from the other roller during the movement imparted by the longitudinal thrust of the arms.

2. In a wringer, the combination of spaced supports, a roller journaled therein, each support being formed with a guiding slot adjacent the roller and with a guiding cam surface leading to the slot, a pair of arms 105 having their free ends movable past the slot, guiding means for the arms, a roller journaled in the free ends of said arms and having journals adapted to contact with and be guided by the cam surfaces into the 110 slots, and means for reciprocating said arms longitudinally to carry the second-mentioned roller toward and away from the first-mentioned roller.

3. In a wringer, the combination with a 115 base, of spaced side frames sustained thereby, each having a plate formed with an upstanding portion and an offset horizontal portion, the horizontal portion of each plate being formed with a longitudinal slot, a 120 roller journaled in the upstanding portions of the plates, an arm movable longitudinally and substantially vertically through each slot, a roller journaled in the upper free ends of the arms, and a lever pivoted to the side 125 frames and connected to said arms for actuating the same.

4. In a wringer, the combination of spaced side frames, each comprising spaced standards, and a connecting plate therefor, each 130

connecting plate being formed with an up-
standing portion and an offset horizontal
portion and a portion pendent from the off-
set portion, the pendent portion being con-
nected to the standards, and each connect-
ing plate being formed with a longitudinal
slot in its horizontal portion, a roller jour-
naled in the upstanding portions of the
plates, an arm movable through each slot,

a roller journaled in the upper ends of the 10
arms, and means for moving said arms lon-
gitudinally through the slots.

In testimony whereof I affix my signature
in presence of two witnesses.
